UNITED STATES PATENT OFFICE

156,008

DESIGN FOR A BAGGAGE RACK

Earl F. Hopkins, Chicago, Ill.

Application April 23, 1947, Serial No. 138,551

Term of patent 14 years

(Cl. D15—8)

To all whom it may concern:

Be it known that I, Earl F. Hopkins, a citizen of the United States, residing at Chicago, in the county of Cook and State of Illinois, have invented a new, original, and ornamental Design for a Baggage Rack, of which the following is a specification, reference being had to the accompanying drawing, forming a part thereof.

Figure 1 is a perspective view taken from one side of a baggage rack, showing my design, and

Figure 2 is a perspective view taken from opposite side of the baggage rack shown in Figure 1.

I claim:

The ornamental design for a baggage rack, substantially as shown.

EARL F. HOPKINS.
